COMBINED PRESSURIZED CONTAINER AND ACTUATOR

Arthur Z. Berenstein, 212 W. 41st St., Erie, Pa. 16508

Continuation-in-part of abandoned design application Ser. No. 227,012, Feb. 16, 1972. This application May 16, 1974, Ser. No. 470,544

Term of patent 14 years

Int. Cl. D9—01

U.S. Cl. D9—9

FIG. I

FIG. 2

FIG. 3

FIG. 1 is a perspective view of a combined pressurized container and actuator showing my new design;

FIG. 2 is a top plan view on a reduced scale; and

FIG. 3 is a side elevational view thereof.

This application is a continuation-in-part of my co-pending application Ser. No. 227,012, filed Feb. 16, 1972, now abandoned.

I claim:

The ornamental design for a combined pressurized container and actuator, as shown and described.
